CLAIM

The ornamental design for a carousel for food packages set, as shown and described.

DESCRIPTION

FIG. 1 is a perspective top view of the carousel for food packages;

FIG. 2 is a right side view of the carousel for food packages of FIG. 1, the left side view being a mirror image thereof; FIG. 3 is a front view of the carousel for food packages of FIG. 1, the back side being a mirror image thereof; FIG. 4 is a top view of the carousel for food packages of FIG. 1;

FIG. 5 is a bottom view of the carousel for food packages of FIG. 1; and,

FIG. 6 is a bottom perspective view of the carousel for food packages of FIG. 1.

The broken lines showing the tab portions of the carousel are for illustrative purposes only and form no part of the claimed design.

The carousel for food packages is typically used in a household setting and is placed in the kitchen. Food packages or pouches, for example, baby food pouches, can be received between its teeth and be hung from its top rim, encircling the top rim.
